ATTORNEY

UNITED STATES PATENT OFFICE.

BENJAMIN K. DORWART, OF LANCASTER, PENNSYLVANIA, ASSIGNOR OF
ONE-FOURTH TO JACOB E. ROTE, OF SAME PLACE.

BOTTLE-STOPPER.

SPECIFICATION forming part of Letters Patent No. 340,201, dated April 20, 1886.

Application filed October 12, 1885. Serial No. 179,678. (No model.)

To all whom it may concern:

Be it known that I, BENJAMIN K. DORWART, a citizen of the United States, residing at Lancaster, in the county of Lancaster and 5 State of Pennsylvania, have invented certain Improvements in Bottle-Stoppers, of which the following is a specification.

My invention relates to a device for dropping or pouring liquids from the mouths of 10 bottles or vessels of a similar character; and the objects of my improvements are, first, to provide a stopper through which liquids can be discharged from or emptied into a vessel without removing said stopper; and, second, 15 to discharge such liquids either by drops or by a continuous stream.

My device is particularly valuable as a means for dropping or pouring medicine from a bottle without removing the stopper, for by 20 it the drops can be delivered of a uniform size and at a uniform rate, while a simple turn of the bottle enables the contents to be poured out in a continuous stream.

I attain the objects mentioned by the mechanism illustrated in the accompanying drawings, in which—

Figure 1 is a side elevation of a bottle with my device attached; Fig. 2, a vertical section through the body of the stopper; Fig. 3, an 30 elevation of the spigot; Fig. 5, an enlarged vertical section of the lower part of the device, and Figs. 4 and 6 show side views of a different arrangement of the tubes. Fig. 7 shows the stopper turned in position to be 35 used as a dropper.

Similar letters refer to similar parts throughout the several views.

A represents the body of my stopper, which consists of a faucet open at both ends, and of 40 such diameter as to enter the mouth of the vessel with which it is used, having a flange, a, encircling it and projecting over the sides of the mouth of the vessel, and two openings, B, in its sides located opposite, or nearly so, 45 to each other, which are adapted to receive tubes b b' of any required size or shape.

Into the top of the faucet A a spigot, D, is

inserted, constructed to fit closely on the same, having openings d through it to correspond with those in the faucet.

The spigot has a milled head, h, and extends to the bottom of the faucet, where a portion, e, of its lower edge is turned outward, so as to lap the part f of the lower edge of the said faucet.

A segment, g, of the lower edge of the faucet is cut away, so as to form a recess, in which a teat, t, which projects from the lower edge of the spigot, engages.

In operating my device the spigot, which 60 is of course closed at the top and open at the bottom, has its movement in the faucet regulated by the teat t and the length of the recess g, the teat resting against the end of the recess, where the openings d of the spigot coincide with those B in the faucet, and against the other when the spigot is turned, so as to completely close the openings B.

The tube b has an orifice just sufficiently large to allow enough fluid to pass through 70 and form drops on the outer end, while the tube b' has an opening great enough to permit a constant flow. In addition to this difference in the capacity of the tubes they are of use for another purpose. The openings in 75 the faucet and spigot being arranged so that those on both sides coincide at the same time, one tube serves to supply air while the other is discharging the fluid.

The operation of my device will be readily 80 understood from the preceding description.

The position of the two parts of the stopper are such that the openings B d coincide when it is desirable to use either tube, and when the outlets are to be closed the spigot is 85 turned by means of its milled head h.

Figs. 4 and 6 show modified forms of my device, the former of which shows a stopper, which can be used for coal-oil or similar cans, and the latter as stoppers for bottles, which 90 it may be wished to fill, or from which the liquid can be transferred without removing the stopper.

The gasket used can be of any desirable ma-

terial, and the relative shape and size of the various parts of my device can be changed, as may be deemed best.

Having thus fully described my said invention, what I claim as new, and desire to secure by Letters Patent, is—

The combination of a hollow metallic stopper open at both ends, and provided with a flange, *a*, and a recess in its lower end, the

tubes *b* *b'* extending therefrom, and the hollow faucet, which fits inside of the stopper, and is provided with openings *d* to correspond with the tubes, and the stop upon its lower end, substantially as shown and described.

BENJ. K. DORWART.
